INVENTOR

DAVID DAVIES,

BY MUNING.

ATTORNEYS

UNITED STATES PATENT OFFICE.

DAVID DAVIES, OF SALT LAKE CITY, UTAH.

WATER-GAGE COCK.

1,078,420.

Specification of Letters Patent. Patented Nov. 11, 1913.

Application filed December 20, 1912. Serial No. 737,854.

To all whom it may concern:

Be it known that I, DAVID DAVIES, a citizen of the United States, and a resident of Salt Lake City, in the county of Salt Lake 5 and State of Utah, have made certain new and useful Improvements in Water-Gage Cocks, of which the following is a specification.

My invention relates to improvements in 10 water gage cocks, and it consists in the combinations, constructions and arrangements herein described and claimed.

An object of my invention is to provide a 15 device having a movable valve member arranged to be brought into registration with an outlet passage to permit the outflow of water or steam with means permitting the removal of the valve while the boiler is still under steam pressure.

20 A further object of my invention is to provide a water gage cock having means for shutting off the flow when the valve is removed, as described above, said means also operating to hold the valve against its seat 25 when the latter is in its operative position.

A further object of my invention is to 30 provide a simple device which is made of few parts, and which therefore is not liable to get out of order.

35 Other objects and advantages will appear in the following specification, and the novel features of the device will be particularly pointed out in the appended claims.

My invention is illustrated in the accompanying drawings forming part of this application in which—

Figure 1 is a section through the gage cock and a portion of the boiler, Fig. 2 is a section similar to that shown in Fig. 1, a portion 40 of the device being removed, Fig. 3 is a section along the line 3—3 of Fig. 1, looking in the direction of the arrow, and Fig. 4 is a perspective view of the valve and valve stem.

45 In carrying out my invention I make use of a boiler of any suitable type.

In Fig. 1 the numeral 1 represents a portion of the boiler wall. This is provided with an opening 1^x arranged to receive the 50 tapered threaded portion 2 of the valve casing 3. The valve casing 3 has a reduced portion 4 provided with a recess 4^x. The tapered threaded portion 2 of the valve casing is provided with a central bore 2^x and at its end has a valve seat 7 arranged to receive a valve 8. The stem of the valve 9 ex-

tends forwardly and is provided at its end with a head 10. A washer or disk 11 is disposed on the valve stem 9, and between the disk 11 and the shoulder 12 on the interior 60 of the valve casing, is a spiral spring 13. This spiral spring tends to hold the valve 8 against its seat.

Referring to Fig. 1, it will be seen that the end of the valve casing consists of a cap 65 portion 14 having a reduced threaded portion 15 arranged to engage the threads 5 of the valve casing 3. In the inner end of the cap 14 is an insert 16 of soft metal such as Babbitt metal. The member 14 has a central bore arranged to receive the valve stem 17 of a valve 18. This valve 18 is provided with an opening 18^x arranged to register with an L-shaped passage 19 in the valve casing 14. This passage extends through a 70 spout 20, as shown in the drawing. The reduced portion 14^x of the cap, however, is provided with a slot 21 in which is disposed the end of a pin 22, which is screwed to the valve stem 17. As will be readily seen from 75 Fig. 3, this gives the pin a certain amount of play and permits the revolution of the valve 90°. The usual hand wheel 23 is provided for turning the valve 18.

From the foregoing description of the 80 various parts of the device the operation thereof may be readily understood. In Fig. 1 I have shown the device as being in the position to permit the passage of water or steam through the channel 19. It is obvious 85 that if the hand wheel 23 be turned 90°, it will bring the stop pin 22 to the end of the slot 21, and will bring the opening 18^x out of registration with the passage 19, thus shutting off the flow of water and steam. 95

The provision of the spring 13 assures the proper seating of the valve 18 upon its seat 16, so as to prevent leakage. When the cap 14 is screwed into position the inner surface of the valve 18 will engage the head 10 and thus force the valve 8 off from its seat, so as to permit a free flow from the boiler into the interior of the valve casing. 100

If it should become necessary at any time to grind the valve 18 or to repair any of the 105 parts connected with the cap 14, the latter is simply unscrewed from the valve casing 3. The spring 13 causes the closure of the valve 8 and the pressure on the inside of the boiler holds the latter against its seat, thereby preventing any escape of water or steam. When the cap 14 is again screwed into place, 110

it will open the valve 8 and restore the apparatus to its normal operative condition. In order to permit the easy manipulation of the device I provide a cap 14 with a squared 5 or hexagonal end for receiving a wrench. The end of the valve casing 3 is also provided with a similar portion 3* (shown in dotted lines) for screwing the tapered portion 2 into the opening 1* in the boiler wall.

10 I claim:

1. The combination with a boiler, of a gage cock comprising a valve casing arranged to be screwed into the wall of the boiler, a cap for said valve casing, a valve 15 arranged to seat against said cap, an auxiliary valve at the inner end of said valve casing, a valve stem for said auxiliary valve arranged to engage said first named valve when the latter is in its operative position, 20 a spring for holding the valve stem against said first named valve, said cap being provided with a conduit, and said first named valve being provided with an opening arranged to register with said conduit, and 25 means carried by said cap for rotating said valve to bring said opening and said conduit into registration.

2. The combination with a boiler, of a gage cock comprising a valve casing arranged to be screwed into the walls of the 30 boiler, a cap for said valve casing having a central bore, and a slot extending laterally from said central bore, a valve arranged to seat against the cap, a valve stem for said valve arranged to extend through the central bore of the cap, a stop pin carried by said valve stem, said stop pin being disposed in the laterally extending slot, an auxiliary valve at the inner end of said valve casing, a valve stem for said auxiliary valve 40 arranged to engage said first named valve when the latter is in its operative position, a spring for holding the valve stem against said first named valve, said cap being provided with a conduit, and said first named 45 valve being provided with an opening arranged to register with said conduit, and a handle for turning the valve stem of the first named valve.

DAVID DAVIES.
